UNITED STATES PATENT OFFICE.

HERBERT W. OWEN AND RALPH N. WELCOME, OF DOVER, NEW HAMPSHIRE, ASSIGNEES TO DRAPER COMPANY, OF HOPEDALE, MASSACHUSETTS, A CORPORATION OF MAINE.

WARPER.

1,026,600.

Specification of Letters Patent.

Patented May 14, 1912.

Application filed February 2, 1912. Serial No. 674,990.

To all whom it may concern:

Be it known that we, HERBERT W. OWEN and RALPH N. WELCOME, both citizens of the United States, and residents of Dover, 5 county of Strafford, State of New Hampshire, have invented an Improvement in Warpers, of which the following description, in connection with the accompanying drawing, is a specification, like characters 10 on the drawing representing like parts.

This invention has for its object the production of simple and effective means for clearing away and removing the lint or fluff which collects in a warper as the warp- 15 threads travel through the usual drop-wires and reed on their way to the beam. As the threads travel through the eyes of the drop-wires the loose particles of lint are scraped off and deposited upon the drop-wires and 20 their support, the lint collecting to such an extent that it not only clogs the wires but may also be picked up and carried along in small bunches by the warp-threads, such 25 deposition and collecting of lint also occurring at the reed, or reeds, when two are used. Heretofore it has been necessary for the warper attendant to remove these collections of lint from time to time, and this 30 is rendered difficult because the lint collects beneath the sheet of warp, so that when a light stick or rod is used to remove the lint, (a common practice) the warp-threads are sometimes caught and broken, and at best 35 the removal of the lint is slow and inefficient, and sometimes necessitates stoppage of the warper.

Our present invention comprehends means to effect automatically the removal of the 40 lint from those portions of the warper where it collects in objectionable quantities, and herein we have provided simple and 45 efficient means for taking up and removing the lint from the vicinity of the reed and drop-wires.

The various novel features of our invention will be fully described in the subjoined specification and particularly pointed out in the following claims.

Figure 1 is a side elevation of a sufficient 50 portion of a warper, with one practical embodiment of our present invention applied thereto, numerous usual parts of the warper not necessary to a proper understanding of our invention being omitted; Fig. 2 is a top 55 plan view, centrally broken out, of the app-

paratus shown in Fig. 1, in so far as it relates to our invention, to illustrate clearly the construction and arrangement of the lint clearing means; Fig. 3 is a detail in front elevation of the means whereby the movement of one clearer is transmitted to the other clearer, as will be explained; Fig. 4 is a perspective view, enlarged, of the detachable brush which may be used for conveniently stripping or cleaning the collected 60 65 lint from the clearer.

The warper herein illustrated is of usual construction, the side frames 1, 1 sustaining the driving shaft 2, (shown in section, Fig. 1,) the shaft 3 which drives the usual drum, 70 not shown, for winding the warp onto the beam 4, the front and back reeds 5, 6 through which the warp-threads 7 travel, the guide-roll 8, tension rolls 9, 9, 9 for the sheet of warp, and the transverse supports 75 or bars 10, 10 on which the two series of drop-wires 11 are pivotally mounted, the parts referred to being all of well known construction and in themselves forming no part of our invention. The drop-wires are 80 pivoted at their lower ends on the supports 10, at the back of the latter, the eyes 12 of said drop-wires receiving the warp-threads, and the forward travel of the latter tends to draw the wires forward with the 85 eyes overhanging the supports, as shown best in Fig. 1. As the sheet of warp passes through the warper a considerable amount of fluff or lint is removed from the threads by the drop-wires and by the reeds, and 90 such lint collects on the supports 10 adjacent the drop-wires and also on and adjacent the reeds. Such deposited lint must be removed from time to time or it will 95 clog and prevent the proper operation of the drop-wires when a thread breaks, and it also clogs the teeth of the reeds, so that there is a tendency to carry small bunches of lint along with the threads to the beam. This lint, in accordance with our present 100 invention, is cleared or removed automatically from the points where it collects, as will now be described.

In accordance with the illustrated embodiment of our invention we attach fixedly 105 to a rotating member of the warper, as the shaft 3, a peripherally grooved sheave 13, around which is passed the bight of an endless flexible clearer 14, having a roughened surface, and in practice we find that a rope- 110

like band of slack-twisted cotton is highly efficient. The sides of the bight of said clearer extend upward from the driving sheave 13 and are carried over two parallel 5 guide sheaves 15, 15 mounted to rotate on horizontal axes sustained by a suitable bracket 16 attached to the left hand side 1 of the warper frame, Figs. 1 and 2. These guide sheaves are so located that the parallel 10 runs 17, 18, Fig. 2, of the clearer will travel above the two supports 10 very close to the same and to the eyes 12 of the two series of drop-wires, but in opposite directions, and in horizontal paths across the top of the 15 warper, but below the sheet of warp 7.

On the righthand frame 1 is bolted a bracket 19, Figs. 2 and 3, which sustains a vertical stud 20 on which is rotatably mounted a horizontal guide sheave 21 around which 20 the clearer 14 is carried, the longitudinal movement imparted to said clearer by the driving sheave 13 causing the sheave 21 to be rotated. Now as the clearer runs 17 and 18 move along adjacent the two series of 25 drop-wires the collected lint is picked up by the roughened surface of the clearer and carried along thereby away from the vicinity of the drop-wires, so that the latter are kept clear and clogging is prevented. 30 The lint adhering to the clearer can be removed from time to time as may be necessary, in any suitable manner, either by stripping the clearer by the hand of the attendant, or by mechanical means. Herein 35 we have shown a mechanical stripper, as a brush 22, the back 23 of which, see Fig. 4, is detachably held preferably in spring clips 24, fastened to the warper side, the clearer traveling over and in contact with the ends 40 of the bristles forming the brush. This stripper brush can be located at any convenient place on the warper, and in Fig. 1 we have shown it so located as to coöperate with the clearer 14 as the latter moves to- 45 ward the driving sheaves 13, but it will be understood that any other desired location may be used. The sheave 21 has attached to it a larger grooved sheave 25, and an adjustable arm 26 on the stud 20 carries a 50 small tension sheave 27, Figs. 2 and 3.

Referring now to Fig. 2, brackets 28 are extended laterally from the frame sides and carry horizontal guide sheaves 29 so located that a tangent to their peripheries will pass 55 just back of and adjacent the back reed 6 adjacent the lower ends of the teeth thereof. A similar bracket 30 at the front of the frame carries a horizontal guide sheave 31, so located that a tangent to it and the large 60 sheave 25 will pass behind and adjacent the lower ends of the teeth of the front reed 5.

An endless reed-clearer 32 is passed around the sheave 25 and the three guide 65 sheaves 29, 31, as clearly shown in Fig. 2,

and the tension sheave 27 is set against said clearer to impart the desired tension thereto. The parallel transverse runs 33, 34 of the clearer 32 thus travel, in opposite directions, across the top of the warper, below the sheet 70 of warp and adjacent the front and back reeds 5, 6 respectively, and as lint collects in the vicinity of the reeds it is taken up and removed by the adjacent portions of said clearer, the reed-clearer being a rope-like member like the clearer for the drop-wires, previously described. The longitudinal movement of the reed-clearer is effected by rotation of the sheave 25, as will be apparent, so that indirectly the 80 reed-clearer is driven by or through the drop-wire clearer through the agency of the attached sheaves 21 and 25.

We have not shown any stripping brush 85 for the reed-clearer, as the latter can be very easily stripped by hand, but if desired a stripper brush such as previously described for the drop-wire clearer can be used for the reed-clearer, and located in 90 any convenient place, as for instance on either of the brackets 28 or 30.

By our invention we dispense with the use of a stick or other device poked under the warp-threads along the drop-wires or reeds, and hence obviate any tendency to injure the warp or the adjuncts of the 95 warper.

Various changes or modifications in details of construction and arrangement may be made by those skilled in the art without departing from the spirit and scope of our invention as set forth in the claims hereto annexed.

Having fully described our invention, 105 what we claim as new and desire to secure by Letters Patent is:

1. The combination, in a warper having a series of drop-wires provided with eyes through which the warp-threads travel, and a fixed support for the said drop-wires and above which their eyes are held by intact warp-threads, of a flexible, rough-surfaced and rope-like endless clearer band, means to sustain a portion thereof immediately above the support for and adjacent the eyes of the drop-wires but below the sheet of warp-threads, and means to effect a continuous longitudinal movement of said clearer band in one direction whereby that portion thereof moving past the drop-wires and above the support therefor collects and removes 115 lint deposited from the warp-threads.

2. In a warper, two series of drop-wires having eyes through which the warp-threads travel and arranged in parallelism, an endless flexible clearer having a rough surface, means to support two portions of the clearer in parallelism below the warp-threads and adjacent the two series of drop-wires, respectively, and means actuated by a moving 125 130

part of the warper to effect continuous longitudinal movement of the clearer, whereby movement of the latter past the drop-wires takes up and clears away the lint deposited 5 in the vicinity of the drop-wires.

3. In a warper, two series of drop-wires having eyes through which the warp-threads travel and arranged in parallelism, an endless flexible clearer having a rough surface, 10 means to support oppositely moving runs of the clearer adjacent the eyes of the two series of drop-wires and below the warp-threads, means to effect continuous longitudinal movement of the clearer, to take up 15 and carry away from the drop-wires the lint deposited adjacent thereto, and a brush across which the clearer travels, to clean the lint therefrom.

4. In a warper front and back reeds 20 through which the warp-threads pass, a series of drop-wires between the reed and coöperating with intact warp-threads, an endless, flexible clearer movable for a part 25 of its length in a path below the warp-threads and adjacent the drop-wires, to collect and remove lint deposited adjacent thereto, a rotatable sheave around which the clearer travels, a second, attached sheave, a second endless clearer traveling around it, 30 means to support the said clearer with two portions thereof adjacent the front and back reeds, respectively, to clear the deposited lint therefrom, and means to effect continuous 35 longitudinal movement of the drop-wire clearer, coöperation thereof with the first sheave effecting longitudinal movement of the reed clearer through the second sheave.

5. In a warper, a reed for the warp-threads, a series of drop-wires coöperating

with intact threads, a clearer to take up and 40 remove lint deposited adjacent the drop-wires, a second clearer operating in like manner for the reed, means to effect operative movement of one of the clearers, and means to effect operative movement of the 45 other clearer by or through the first-mentioned clearer.

6. In a warper, a reed for the warp-threads, a series of drop-wires coöperating with intact threads, an endless, flexible 50 clearer having a roughened surface and movable longitudinally adjacent the drop-wires, to collect and remove lint deposited adjacent thereto, a second similar clearer movable longitudinally adjacent the reed to 55 collect and remove lint therefrom, means to drive one of said clearers, and means to drive the other clearer by or through longitudinal movement of the first one.

7. In a warper having a reed through 60 which the warp-threads travel, and a series of drop-wires coöperating with intact threads, in combination, two clearers operating automatically adjacent said reed and drop-wires, respectively, and beneath the 65 sheet of warp, to take up and remove the lint collecting adjacent the reed and drop-wires, and means to effect the operation of the clearers.

In testimony whereof, we have signed our 70 names to this specification, in the presence of two subscribing witnesses.

HERBERT W. OWEN.
RALPH N. WELCOME.
